STAPLE REMOVER

Louis von Cseh, New York, N. Y., assignor to
Speed Products Company, Inc., Long Island
City, N. Y., a corporation of New York

Application July 23, 1945, Serial No. 606,527

20 Claims. (Cl. 254—28)

1

This invention is an improved staple remover and the objects, advantages and functional and structural features thereof will be better understood from the following detailed description considered in the light of the accompanying drawing wherein:

Fig. 1 is a side view of the staple remover according to my invention, illustrating the plunger raised and the rectilinearly displaceable elevator depressed prior to removing a clinched staple.

Fig. 2 is a view similar to Fig. 1 but showing the slidably guided plunger depressed and the elevator raised extracting a staple.

Fig. 3 is a fragmentary front view of Fig. 1.

Fig. 4 is a fragmentary front view of Fig. 3 showing the elevator extracting a staple.

Fig. 5 is an enlarged vertical sectional view of Fig. 1 illustrating the elevator depressed.

Fig. 6 is an enlarged vertical sectional view of Fig. 2 showing the elevator raised and the plunger depressed.

Fig. 7 is a horizontal transverse sectional view on the line 7—7 of Fig. 5.

Fig. 8 is a rear elevational view of Fig. 5.

Fig. 9 is a cross sectional view on the line 9—9 of Fig. 8.

Fig. 10 is a cross sectional view on the line 10—10 of Fig. 8, and

Fig. 11 is a side view of the support.

The staple remover broadly designated R comprises a support S, a reciprocably guided plunger P, a vertically and rectilinearly guided elevator E and a closure or cap C.

The support S is a channel shaped member having a rear wall 10 integrally merged with the forwardly extending and spaced walls 11 defining the opening 12.

Extending forwardly of and integrally with the rear wall 10 but spaced from the biased and lower ends 13 of the sides 11 of the support S is the bottom plate or sustaining member 14 having forwardly extending and spaced rectilinear projections or lugs 15 provided with tapering terminals 16 having the outer sides 17 converging forwardly and their outer corners 18 rounded as shown in Fig. 9.

Lugs 15 define a gap 19 for removably receiving the rectilinear staple lifting tongue 20 offset from lug 21 extending forwardly of and integral with the hollow boss or rib 22 of the elevator E.

Extending laterally of boss 22 and integral therewith are the wings 23 slidably retained against the rear wall 10 of the support S by the spaced inwardly crimped portions or ribs 24 struck into the sides 11. To further insure proper

2

slidable displacement of the elevator E relative to the support S the spaced sides 11 of the latter each embodies an elongated slot 25 slidably guiding the laterally extending lugs 26 integral with and projecting from the wings 23.

Journalized to the spaced sides 11 of the U-shaped support S is the rotatable shaft 30 carrying pinion 31 in mesh with teeth 32 of the elevator E and the teeth 33 of the inwardly depressed portion 34 10 of the plunger P. In effect it may be said that the pinion 31 is actuated or driven by the rack defined by the teeth 33 of the plunger P and when so actuated, causes the displacement of the rack defined by teeth 32 of the hollow rib 22 of the reciprocal elevator.

The plunger P is a hollow substantially square shaped casing wherein its front wall 35 embodies the depressed portion 34 and its side walls 36 closely but slidably straddle the spaced sides 11 of 20 the support S while its rear wall 37 slidably engages the rear wall 10 of the support S. In other words, the plunger P telescopically receives a part of the support and is slidably guided thereon although it is normally held in a raised or elevated 25 position by the tapered helicoidal spring 38 having an end seated on the top faces 39 and 40 of the spaced sides 11 and the wall 10 of the support, and having its narrower end retained by a cap C anchored to the plunger by the crimped portion 42. Detents as 43 are bent inwardly from the rear wall 10 and the spaced side walls 11 of the support S and serve to prevent slippage of the lower part of the spring into the channel 12 defined by the side walls 11 of the support. To prevent removal of the plunger from the support 30 fastening means in the form of a set screw 44 is fastened to and carried by the rear wall 37 of the plunger and this set screw extends into the elongated guide slot 45 of the rear wall 10 of the support S.

By the arrangement disclosed, the plunger is normally held raised by the spring 38. In such relation tongue 20 and its tapered terminal 46 are coplanar with that is, in the same plane as the lugs 15 and the tapered terminals 16 respectively at which time lug 21 of the elevator E is resting on the seat or sustaining member 14 which embodies the spaced depressed portions or ribs 47 and 48 adapted to sustain the staple remover upright when not in use. However, when in use of the staple remover the latter may be tilted on rib 47 which serves as fulcrum means.

Prior to withdrawing a staple 50 anchoring sheet material 51 the staple remover is rocked on rib 47 as explained above to present the ter-

terminal 46 of the lifting member 20 and the terminals 16 of lugs 15 in a downwardly inclined relation to permit these terminals 16 and 46 to be readily and slidably received under the bridge 52 of the staple and between legs 53 thereof (Fig. 3). Thereafter the plunger P is depressed by applying finger pressure on the cap C. Hence the plunger is slidably displaced downwardly against the resistance of the tapered and helicoidal spring 38. The rack defined by the teeth 33 thus moves downwardly rotating pinion 31 counterclockwise and the rack defined by teeth 32 of the hollow boss 22 moves upwardly. Thus the staple lifting member 20 is elevated out of the gap 19. By this action the bridge 52 of the wire staple 50 is lifted and the lower portions of the legs 53 of the formerly clinched staple are diverged and withdrawn from the material 51.

Pursuant to the extraction or removal of a clinched staple, finger pressure is removed from the cap C, the spring thus again expands, elevating the plunger, and the pinion 31 is driven clockwise, driving the elevator E downwardly whereby lug 21 again is moved onto the seat 14 of the support and the staple lifting tongue or member 20 is again moved automatically into gap 19 to be flush with projections or lugs 15.

From the foregoing disclosure it is apparent that the herein stapling remover has as its dominant aspect the ease of removing a clinched staple from material which may be solid or sheet form by merely applying a downwardly directed pressure or thrust on the slideable plunger after the positioning of the staple lifting tongue 20 and the aligned lugs 15 under the bridge of the clinched staple. Another important functional and structural aspect of the invention is realized in automatically and vertically lifting a reciprocably guided staple extracting elevator upon the displacement of the plunger in an opposite direction.

Various changes may be made in details of construction and arrangement of parts without departing from the spirit of the invention or sacrificing any of the advantages thereof inherent therein.

I claim:

1. In a staple remover, a support having spaced lugs, staple lifting means, a plunger, means for slidably guiding said plunger on said support, means for slidably guiding said staple lifting means relative to said support, and means for actuating said staple lifting means in a linear direction away from said lugs upon slideable displacement of said plunger relative to said support.

2. In a device for removing a clinched staple having a bridge and bent legs, a support having spaced lugs adapted to be inserted under said bridge and between said legs, an elevator having a staple lifting tongue removably disposed between said lugs and adapted to be inserted under said bridge, a plunger, means for slidably guiding said plunger on said support, means for slidably guiding said elevator relative to said support, and means for actuating said elevator upon displacement of said plunger relative to said support whereby said tongue lifts said bridge and said legs straddle and are lifted along and beyond the sides of said lugs.

3. In a staple remover, a support having a seat including spaced lugs defining a gap, an elevator having a tongue removably interposed in said gap, a plunger, means for slidably guiding said plunger on said support, means for slidably guiding said elevator relative to said support, means for actuating said elevator upon displacement of

said plunger relative to said support, and means for normally holding said tongue in said gap.

4. In a staple remover, a support having a seat including spaced ribs and including spaced lugs, an elevator having a tongue removably interposed between said lugs, a plunger, means for slidably guiding said plunger on said support, means for slidably guiding said elevator relative to said support, means for actuating said elevator upon displacement of said plunger relative to said support to raise said tongue in a direction towards said plunger for withdrawing said tongue from between said lugs.

5. In a device for removing a clinched staple, a support having a forwardly projecting seat including spaced lugs and having rib means, an elevator having a tongue removably interposed between said lugs, a plunger, means for slidably guiding said plunger on said support, means for slidably guiding said elevator relative to said support, means for actuating said elevator upon displacement of said plunger relative to said support to raise and withdraw said tongue relative to and from said lugs, and said rib means characterizing a fulcrum, means for bodily tilting said remover to dispose said tongue and lugs in an inclined relation relative to said staple.

6. In a device for removing a clinched staple having a bridge and bent legs, a support having a forwardly projecting seat including spaced lugs adapted to be inserted under said bridge and between said legs, an elevator having a staple lifting tongue removably disposed between said lugs and adapted to be inserted under said bridge, a plunger, means for slidably guiding said plunger on said support, means for slidably guiding said elevator relative to said support, means for actuating said elevator upon displacement of said plunger relative to said support whereby said tongue lifts said bridge and said lugs straddle and are lifted along and beyond the sides of said lugs, and spring means interposed between said plunger and support for normally holding said plunger elevated and said elevator against said seat.

7. In a device for removing a clinched staple having a bridge and bent legs, a support having a forwardly projecting seat including spaced lugs adapted to be inserted under said bridge and between said legs, fulcrum means depending from said seat for tilting said support, an elevator having a staple lifting tongue removably disposed between said lugs and adapted to be inserted under said bridge, a plunger, means for slidably guiding said plunger on said support, means for slidably guiding said elevator relative to said support, means for actuating said elevator upon displacement of said plunger relative to said support whereby said tongue lifts said bridge and said legs straddle and are lifted along and beyond the sides of said lugs, and spring means for normally holding said elevator against said seat and said tongue between said lugs.

8. In a device for removing a clinched staple having a bridge and bent legs, a support having a forwardly projecting seat including spaced lugs adapted to be inserted under said bridge and between said legs, a shaft journaled to said support, a pinion mounted on said shaft, an elevator including a rack in mesh with said pinion and having a staple lifting tongue removably disposed between said lugs and adapted to be inserted under said bridge, a plunger, a rack on said plunger in mesh with said pinion, means for slidably guiding said plunger on said support, and means for slidably guiding said elevator relative to said support,

the rack on said plunger on the displacement of the latter towards said lugs rotating said pinion for actuating the rack on said elevator whereby said tongue lifts said bridge and said legs straddle and are lifted along and beyond the sides of said lugs.

9. In a device for removing a clinched staple having a bridge and bent legs, a support having a forwardly projecting seat including spaced lugs adapted to be inserted under said bridge and between said legs, an elevator having a staple lifting tongue removably disposed between said lugs and adapted to be inserted under said bridge, a plunger, means for slidably guiding said plunger on said support, means for slidably guiding said elevator relative to said support, and rack and pinion means common to said elevator and plunger for actuating said elevator upon displacement of said plunger relative to said support whereby said tongue lifts said bridge and said legs straddle and are lifted along and beyond the sides of said lugs.

10. In a device for removing a clinched staple having a bridge and bent legs, a support having a forwardly projecting seat including spaced lugs adapted to be inserted under said bridge and between said legs, an elevator having a staple lifting tongue removably disposed between said lugs and adapted to be inserted under said bridge, a plunger, means for slidably guiding said plunger on said support, means for slidably guiding said elevator relative to said support, a pinion, means rotatably sustaining said pinion, and spaced rack means in mesh with said pinion for actuating said elevator upon displacement of said plunger relative to said support whereby said tongue lifts said bridge and said legs straddle and are lifted along and beyond the sides of said lugs.

11. In a staple remover, a support having an upstanding wall including forwardly extending sides and having a forwardly projecting seat including spaced lugs defining a gap, an elevator having a tongue removably interposed in said gap and normally coplanar with said lugs, a plunger, means for slidably guiding said plunger on said support, rack and pinion means common to said plunger and elevator, and spring means for holding said plunger raised for automatically positioning said tongue between said lugs.

12. In a staple remover, a support having an upstanding wall including forwardly extending sides and having a forwardly projecting seat including spaced lugs defining a gap, a shaft rotatably carried by said support, a pinion secured to said shaft, an elevator having a tongue removably interposed in said gap and normally coplanar with said lugs, a plunger having a rack, means for slidably guiding said plunger on said support, spaced racks on said elevator and plunger in mesh with said racks, and spring means for holding said plunger raised for automatically positioning said tongue between said lugs.

13. In a device for removing a staple, a support having an upstanding wall including forwardly extending sides and having a forwardly projecting seat including spaced lugs defining a gap, an elevator having a tongue removably interposed in said gap and normally coplanar with said lugs, a plunger, means for slidably guiding said plunger on said support, rack and pinion means common to said plunger and elevator, spring means for holding said plunger raised for automatically positioning said tongue between said lugs, and means depending from said seat for bodily sus-

taining said lugs and tongue tilted relative to said staple.

14. In a device for removing a clinched staple having a bridge and bent legs, a support comprising a rear wall provided with forwardly projecting and spaced sides, a seat at the lower part of said wall and spaced from said sides and including spaced and forwardly projecting lugs adapted to be inserted under said bridge and between said legs, an elevator displaceable linearly relative to said support and comprising a channeled member including an upstanding boss and a staple lifting tongue substantially normal to said boss and removably disposed between said lugs and adapted to be inserted under said bridge; a plunger having spaced and outer sides closely straddling but slidably guided by said forwardly projecting sides, said support and elevator having means to slidably and linearly guide the latter relative to said support, a pinion, a shaft journaled to said spaced and outer sides and carrying said pinion, and spaced rack means carried by said plunger and boss and in mesh with said pinion for linearly raising said elevator upon linear downward displacement of said plunger relative to said support whereby said tongue lifts said bridge and said legs straddle and are lifted along and beyond the sides of said lugs.

15. In a device for removing a clinched staple having a bridge and bent legs, a support comprising a rear wall provided with forwardly projecting and spaced sides, a seat at the lower part of said wall and spaced from said sides and including spaced and forwardly projecting lugs adapted to be inserted under said bridge and between said legs, an elevator displaceable linearly relative to said support and comprising a channeled member including an upstanding boss and a staple lifting tongue substantially normal to said boss and removably disposed between said lugs and adapted to be inserted under said bridge; a plunger having spaced and outer sides closely straddling but slidably guided by said forwardly projecting sides, said support and elevator having means to slidably and linearly guide the latter relative to said support, a pinion, a shaft journaled to said spaced and outer sides and carrying said pinion, spaced rack means carried by said plunger and boss and in mesh with said pinion for linearly raising said elevator upon linear downward displacement of said plunger relative to said support whereby said tongue lifts said bridge and said legs straddle and are lifted along and beyond the sides of said lugs, and plunger for normally holding the latter elevated to arrange said tongue substantially coplanar with said lugs.

16. In a device for removing a clinched staple having a bridge and bent legs; a support comprising a rear wall provided with forwardly projecting and spaced sides including vertically arranged hollow ribs, and a seat at the lower part of said wall and spaced from said sides and including spaced and forwardly projecting lugs adapted to be inserted under said bridge and between said legs; an elevator displaced linearly relative to said support and comprising a channeled member including an upstanding boss and a staple lifting tongue substantially normal to said boss and removably disposed between said lugs and adapted to be inserted under said bridge and embodying wings extending laterally of said boss and slidably guided by said ribs, a plunger having spaced and outer sides closely straddling but slidably guided by said forwardly projecting

7 sides, a pinion, a shaft journaled to said spaced and outer sides and carrying said pinion, and spaced rack means carried by said plunger and boss and in mesh with said pinion for linearly raising said boss upon linear downward displacement of said plunger relative to said support whereby said tongue lifts said bridge and said legs straddle and are lifted along and beyond the sides of said lugs.

17. In a device for removing a clinched staple having a bridge and bent legs, a support comprising a rear vertical wall provided with forwardly projecting and spaced vertical sides, a seat at the lower part of said wall and spaced from said sides and including spaced and forwardly projecting horizontally disposed lugs adapted to be inserted under said bridge and between said legs, an elevator displaceable linearly relative to said support and comprising a vertically arranged channelled member including a staple lifting forwardly extending tongue substantially normal to said boss and removably disposed between and normally coplanar with said lugs and adapted to be inserted under said bridge; a hollow rectilinear shaped plunger having spaced and outer sides closely straddling but slidably guided by said forwardly projecting sides, said support spaced ribs for slidably and linearly guiding said elevator relative to said support, a pinion, a shaft journaled to said spaced and outer sides, and carrying said pinion, and spaced means carried by said plunger and boss and in mesh with said pinion for linearly raising said elevator upon linear downward displacement of said plunger relative to said support whereby said tongue lifts said bridge and said lugs straddle and are lifted along and beyond the sides of said lugs.

18. The device according to claim 17 wherein the rear wall of said support embodies a vertically arranged slot, and said plunger is provided with a pin slidably guided by the walls of said slot and the ends of the latter cooperating with said pin to limit linear displacement of the plunger.

19. The device according to claim 17 wherein the rack means of said boss is on a forwardly disposed wall of the latter and the rack means of the plunger is on an indented portion of the front wall of the plunger.

20. The device according to claim 17 wherein a cap is mounted and retained by the upper part of the plunger, and a helicoidal spring is interposed between the plunger and cap for normally holding the plunger elevated at which time said tongue is coplanar with said spaced lugs.
